(57) **CLAIM**

The ornamental design for a mirror, as shown and described.

DESCRIPTION

FIG. 1 is front elevation view showing my new design. FIG. 2 is a left side elevation view of the mirror of FIG. 1, the right side elevation view being a mirror-image. FIG. 3 is a top end view of the mirror of FIG. 1.

FIG. 4 is a rear elevation view of the mirror of FIG. 1. FIG. 5 is a bottom end view of the mirror of FIG. 1; and, FIG. 6 is a partial cross-sectional view of the mirror taken along lines 6—6 in FIG. 1.

The portions of the drawings appearing in broken lines are for environment only and do not form a part of the claimed design.
